CLAIM

We claim the ornamental design for an enclosure for network interface controller, as shown and described.

DESCRIPTION

FIG. 1 is a front, top, right side isometric view of the enclosure for network interface controller in an open position, according to a first embodiment;

FIG. 2 is a rear, bottom, left side isometric view of the enclosure for network interface controller in the open position, according to the first embodiment;

FIG. 3 is a top view of the enclosure for network interface controller in the open position, according to the first embodiment;

FIG. 4 is a bottom view of the enclosure for network interface controller in the open position, according to the first embodiment;

FIG. 5 is a front view of the enclosure for network interface controller in the open position, according to the first embodiment;

FIG. 6 is a rear view of the enclosure for network interface controller in the open position, according to the first embodiment;

FIG. 7 is a right side view of the enclosure for network interface controller in the open position, according to the first embodiment;

FIG. 8 is a left side view of the enclosure for network interface controller in the open position, according to the first embodiment;

FIG. 9 is a front, top, right side isometric view of the enclosure for network interface controller in a closed position, according to the first embodiment;

FIG. 10 is a rear, bottom, left side isometric view of the enclosure for network interface controller in the closed position, according to the first embodiment;

FIG. 11 is a top view of the enclosure for network interface controller in the closed position, according to the first embodiment;

FIG. 12 is a bottom view of the enclosure for network interface controller in the closed position, according to the first embodiment;

FIG. 13 is a front view of the enclosure for network interface controller in the closed position, according to the first embodiment;

FIG. 14 is a rear view of the enclosure for network interface controller in the closed position, according to the first embodiment;

FIG. 15 is a right side view of the enclosure for network interface controller in the closed position, according to the first embodiment; and,

FIG. 16 is a left side view of the enclosure for network interface controller in the closed position, according to the first embodiment.

Broken lines immediately adjacent to the claimed surfaces represent boundaries of the claimed design. All other broken lines depict unclaimed environment. The broken lines and unshaded surfaces bounded by broken lines form no part of the claimed design.
